Primary Examiner — Marissa J. Cash*Assistant Examiner* — Kayla Marie Bennett(57) **CLAIM**

The ornamental design for a multi-tool carabiner, as shown and described.

DESCRIPTION

FIG. 1 is a perspective view of a multi-tool carabiner showing the new design;

FIG. 2 is another perspective view thereof;

FIG. 3 is a front elevation view thereof;

FIG. 4 is a back elevation view thereof;

FIG. 5 is a left-side view thereof;

FIG. 6 is a right-side view thereof;

FIG. 7 is a top plan view thereof;

FIG. 8 is a bottom plan view thereof; and,

FIG. 9 is a view of the multi-tool carabiner in a folded position.

The broken lines depict portions of the multi-tool carabiner that form no part of the claimed design.

1 Claim, 9 Drawing Sheets(56)
